UNITED STATES PATENT OFFICE.

PAUL DAVIS, OF VIRGINIA CITY, VIRGINIA, ASSIGNOR OF ONE-THIRD TO JACOB W. FRANKS, ONE-EIGHTH TO J. S. HORNE AND CARL HORNE, ALL OF COEBURN, VIRGINIA, AND ONE-HALF TO S. ASTON, OF LEBANON, VIRGINIA.

STEAM TURBINE.

Application filed February 6, 1924. Serial No. 690,987.

This invention relates to turbines of the velocity type, in which the steam or other motive fluid is applied directly to the periphery of the rotor or turbine wheel in a 5 circumferential direction.

The primary object of the invention is to provide a reversible turbine in which the buckets or vanes are so constructed that a maximum amount of power will be derived 10 from the turbine irrespective of the direction of rotation of the rotor with the use of a minimum amount of steam.

A further object of the invention is to provide novel means for hingedly mounting the 15 buckets or vanes on the rotor, whereby the position of the buckets will be automatically reversed upon the changing of the path of the steam to reverse the direction of rotation of the rotor.

20 A still further object of the invention is the provision of an improved turbine of the above character, which will be durable and efficient in use, one that will be simple and easy to manufacture, and one which can be 25 placed upon the market at a small cost.

With these and other objects in view, the invention consists in the novel construction, arrangement and formation of parts, as will be hereinafter more specifically described, 30 claimed and illustrated in the accompanying drawings, in which:

Figure 1 is an end elevation of the improved turbine.

Figure 2 is a longitudinal section through 35 the turbine taken on the line 2-2 of Figure 1.

Figure 3 is a transverse section through the turbine taken on the line 3-3 of Figure 2.

40 Figure 4 is a longitudinal section through the valve construction.

Figure 5 is a transverse section through the valve construction taken on the line 5-5 of Figure 4.

45 Figure 6 is a detail end elevation of the turbine illustrating the means employed for shifting the control valve, and

Figure 7 is a fragmentary plan view of the turbine partly in section illustrating the 50 guide for the valve shifting lever.

Referring to the drawings in detail wherein similar reference characters designate corresponding parts throughout the several views, the letter A generally indicates the

improved turbine, which comprises the stator 55 B. The rotor C carrying the novel buckets or vanes D; the valve controlling mechanism E, and the valve shifting means F.

The stator B comprises an annular side wall 10 which can be bolted or otherwise 60 secured to a suitable base frame 11. The opposite faces of the annular side wall 10 have bolted or otherwise secured thereto such as by cap screws 12, the disk-shaped 65 end plates 13 and 14.

The end plates 13 and 14 are provided with axial bearings 15, which rotatably receive the power shaft 16. The bearings 15 can be provided with suitable stuffing boxes 17, in order to prevent the leakage of steam 70 from between the rotor and the stator.

The rotor C includes a solid hub 18 which is keyed or otherwise secured to the power shaft 16 and the periphery of the hub 18 is provided at equidistantly spaced points with 75 transversely extending supporting lugs 19 the opposite faces of which are gradually tapered toward the outer ends of the lugs. The ends of the hub 18 are provided with annular flanges 20 which receive the ends of 80 the lugs 19 and project radially beyond the same.

The lugs 19 form supports for the vanes or buckets D, which will now be described. These vanes or buckets D are all of the same 85 construction and each includes a substantially semi-cylindrical body 21 and a longitudinally extending centrally disposed rib 22. It is to be noted that the rib 22 is secured to the concaved face of the semi-cylindrical body 21 of the vane or bucket. The terminals of the rib 22 are provided with hinge lugs or pins 23 which are fitted within suitable bearing openings formed in the inner faces of the flanges 20. By this 90 construction, it is obvious that the position of the vanes or buckets D can be reversed relative to the hub 18, so that the steam entering into the stator can impinge against the concave faces of the vanes or buckets irrespective of the direction of rotation of the rotor. When the vanes or buckets 100 assume an operative position their swinging movement is limited by the body portions thereof contacting with the hub 18 of the 105 rotor.

The valve structure E is utilized both for the purpose of controlling the steam enter-

ing into the stator and for regulating the direction of flow of the steam into the stator for causing the reversing of the rotor and embodies a cylindrical housing 25 which is arranged above the stator at the longitudinal axis thereof. This hollow cylindrical casing 25 has communicating therewith at spaced points the diverging feed pipes 26 and 27 which lead into the stator on opposite sides of the vertical center thereof. One end of the casing 25 has connected therewith an inlet nipple 28 which is provided with a valve seat 29. This inlet nipple 28 has connected therewith the steam inlet pipe 30. A valve plug 31 is mounted within the casing 25 for rotary and sliding movement and has one side thereof cut away to provide a feed channel 32. By referring to Figure 4 it can be seen that the feed channel 32 ends short of one end of the valve plug. The opposite end of the valve plug 31 is provided with a conical valve 33 which is adapted to fit upon the valve seat 29 formed in the nipple 28. Thus when the conical valve 33 rests on the valve seat 29 the entrance of steam into the casing 25 and consequently into the stator B from the inlet pipe 30 is prevented. An axially disposed stem 34 is formed on the valve plug 31 and projects outwardly from the casing 25 through a suitable stuffing box 35. By turning the valve plug 31 so as to move the channel 32 over the pipe 26 or 27 the direction of flow of steam into the stator can be regulated.

The improved means F for shifting the valve plug 31 comprises a lever 36, which is rockably mounted on a yoke 37 at a point intermediate its ends. This yoke 37 is in turn slidably mounted upon a bracket 38 which can be bolted or otherwise secured to the stator B. The lever 36 is therefore mounted for swinging movement in two directions. The upper end of the lever 36 is provided with a yoke 39 which straddles the valve stem 34 and the yoke is connected to the valve stem 34 through a suitable pin and slot connection 40. The lower end of the lever projects through an I-slot 41 in a guide plate 42 which is also bolted to the stator. A hand grip 43 is formed on the lever for facilitating the shifting movement thereof.

When it is desired to permit entrance of steam into the stator B, say through the pipe 26 for causing the rotation of the rotor in a counter-clockwise direction the hand grip 43 is grasped by the operator of the turbine and swung to the right, which will rotate the valve plug 31 so that the channel 32 will overlie the feed pipe 26. This shifting movement of the lever will position the same at one end of the eye slot 41 which will permit the handle to be shoved in-

wardly causing the unseating of the valve plug 33. The steam will now enter the casing 25 from the inlet pipe 30 into the feed pipe 26 and then into the casing. The steam will now impinge against the concaved faces of the buckets and cause the rotor to rotate in a high velocity in a counter-clockwise direction in the stator. The spent steam is permitted to escape from the stator through a suitable exhaust port 44 formed in the lower end thereof.

When the device is operated at full speed the vanes at the right, in Figure 2, project radially due to centrifugal force and when the rotor comes to rest, the vanes to the right will fall into operative position for clockwise direction.

When it is desired to reverse the direction of the rotor, it is merely necessary to shift the lever 36 to the other end of the guide plate 42 and push the same inwardly, which will position the channel 32 over the feed pipe 27 and unseat the valve 33. The steam will now flow into the stator B through the pipe 27 causing the steam to impinge against the concave faces of the bucket B which will turn the rotor in a clockwise direction. As the rotor gains momentum the buckets will assume the position shown in Figure 2 due to the centrifugal action and the buckets will not reverse by gravity. When the rotor comes to rest, the vanes will fall into operative position for a counter-clockwise direction.

From the foregoing description, it can be seen that I have provided an exceptionally simple turbine of a compact nature, in which the reversing thereof is accomplished with a minimum amount of effort.

Changes in details may be made without departing from the spirit or the scope of this invention.

What I claim as new is:

1. In a reversible turbine, a rotor including a hub, a plurality of buckets extending transversely of the hub including central ribs pivoted to the periphery of the hub and substantially semi-cylindrical bodies having convex outer faces and concaved inner faces.

2. In a reversible turbine, a stator, a rotor mounted within the stator comprising a cylindrical body including a hub, and side flanges extending beyond the hub, the periphery of the hub being provided at spaced points with transversely extending ribs joining the side flanges, a plurality of buckets extending transversely of the hub arranged between the side flanges including a central rib pivotally secured to the ribs on the hub, and a substantially semi-cylindrical body including an outer convex face and an inner concave face.

In testimony whereof I affix my signature.

PAUL DAVIS.
